UNITED STATES PATENT OFFICE.

VINTON PHENIX, OF GREELEY, COLORADO.

CASKET-LOWERING DEVICE.

Application filed October 6, 1925. Serial No. 60,707.

This invention relates to a device for lowering caskets into graves.

There are at present devices upon the market for this purpose. These devices, however, are operated by gravity, that is, by the weight of the casket and body, and cannot be used for caskets containing the light bodies of children as there is not sufficient weight to operate the mechanism.

10 The principal object of this invention is to provide a device of this character which will be especially applicable to the lowering of caskets containing the bodies of children.

15 Another object is to provide a device of this character which will be operated by externally applied power so that the descent of the casket will be controlled by the amount of power applied and not by the weight of the casket.

20 Other objects and advantages reside in the detail construction of the invention, which is designed for simplicity, economy, and efficiency. These will become more apparent 25 from the following description.

In the following detailed description of the invention reference is had to the accompanying drawing which forms a part hereof. Like numerals refer to like parts in all views 30 of the drawing and throughout the description.

In the drawing:

Fig. 1 is a perspective view of an open grave illustrating the device ready for use.

35 Fig. 2 is a plan view of the device.

Fig. 3 is an enlarged end elevation thereof, the gear housing being shown in section.

40 Fig. 4 is a detail view of a tape tension device which may be employed in connection with the invention.

The invention comprises an open frame 10 of the proper size to fit around the opening of a grave, such as illustrated at 11. Journaled as shown at 34, along each side of the frame 10, are hollow shafts 12 and 13. Two tapes 14, extend between and coil around, the shafts 12 and 13.

45 The shafts 12 and 13 are caused to simultaneously operate in opposite directions by means of a crossed chain 15 operating over sprockets 35 carried on the shafts 12 and 13. The shaft 13 also carries a small spur pinion 16 which meshes with a countershaft gear 17 secured on a short countershaft 18.

A countershaft pinion 19 is also carried secured on the countershaft 18 and meshes with a drive gear 20 secured on a short drive shaft 21. An operating lever 22 is secured to the drive gear 20 and the drive shaft 21. 60

The gear ratio of the described gearing is such as to cause the shafts 12 and 13 to revolve a sufficient number of times to lower the tape 14 to the bottom of the grave while the lever 22 is being moved through an arc 65 of slightly less than 180°.

A spool 23 is secured on the drive shaft 21 about which a flexible cable 24 winds as the tape 14 descends into the grave. The extremity of the cable 24 connects with a tension spring 25. The pull of the spring 25 tends to draw the lever 22 to the extreme right hand position and keep the tapes 14 taut. The strength of the spring 25 is such as to support a casket of the maximum 70 weight for which the particular device is designed so that, should the operating handle be released at any point, the weight of the casket will be insufficient to operate the device. 75

In operation, a casket is rested upon the tapes 14 over the open grave. It is supported by the tapes 14, which are prevented from descending by the action of the spring 25, the friction of the gearing, and a notch 26 80 in a segment 27 in which the lever 22 is engaged. When it is desired to lower the casket the lever is disengaged from the notch 26 and raised. This action results in stretching the spring 25 and unwinding the tapes 90 14 from the shafts 12 and 13. Should it be desired to arrest the descent of the casket midway for the funeral services, the lever 22 is allowed to engage in a second notch 28 in the segment 27, from which position, it 95 is moved to a third notch 29 at which time the casket will rest on the floor of the grave.

It is desired to impress the fact that operation of the device does not depend upon, nor is it operated by, the weight of the casket, but 100 that the device is forced to lower the casket by manual power applied to the lever 22.

To cause the tapes 14 to uniformly build up as they reel upon the shafts 12 and 13, I 105 prefer to employ two upstanding reel guides 31, secured at their lower extremities to the frame 10 and arrangement to snugly engage the tape as it winds upon the shafts. To cause the tapes to wind in a tight reel, I provide a leaf spring 32 preferably carried by 110

the members 31 and arranged to constantly contact with the surface of the tape as it winds upon the shafts.

While a specific form of the improvement has been described and illustrated herein, it is desired to be understood that the same may be varied, within the scope of the appended claim, without departing from the spirit of the invention.

10 Having thus described the invention, what I claim and desire secured by Letters Patent is:

In a casket lowering device having a frame adapted to surround a grave, and parallel

rotatable bars connected by bands carried by said frame, a chain causing said bars to operate in unison and in opposite directions; a countershaft operatively connected to one of said bars; a drive shaft operatively connected to said countershaft; a crank secured to said drive shaft; an expansible spring fixedly secured at its one extremity; and a flexible medium secured to the other extremity and adapted to wind upon said drive shaft, said crank being prevented from arcuate movement exceeding 180°.

In testimony whereof, I affix my signature.

VINTON PHENIX.
